UNITED STATES PATENT OFFICE

2,370,564

SIGNAL REPRODUCING APPARATUS

Carroll R. Miner, Stratford, Conn., assignor to
 General Electric Company, a corporation of
 New York

Application December 24, 1943, Serial No. 515,499

7 Claims. (Cl. 179—100.11)

My invention relates to electric signal receiving and reproducing apparatus, more particularly to combination radio and phonograph receiving and reproducing apparatus, and has for its principal object the provision of a simplified and inexpensive, but none the less reliable, discriminatory and sensitive apparatus of the character described.

Heretofore it has been common practice in combination radio and phonograph receiving and reproducing sets of relatively expensive design to provide a volume control resistor which may be selectively switched to connection either with the phonograph pick-up or with the radio receiving apparatus. Such switching apparatus constitutes an element of complication and cost which is desirably eliminated in less expensive sets. According to my invention, a permanent connection for the phonograph pick-up is provided and switching is avoided without introducing excessive loading of the phonograph signal or objectionable interference by the radio signal during phonograph reproduction.

The nature of my invention and the mode of its operation will be more fully understood and its objects and advantages further appreciated by referring now to the following detailed specification taken in conjunction with the accompanying drawing, in which Fig. 1 is a schematic circuit diagram of a combined radio and phonograph signal reproducing apparatus embodying my invention in one form, and Fig. 2 is a similar circuit diagram showing another embodiment of my invention.

Referring now to the drawing, and particularly to Fig. 1, I have shown an electron discharge device 10 as representative of a suitable source of signal modulated electric oscillations. By way of example, the discharge device 10 may be the last intermediate frequency amplifier of a radio receiving apparatus of the super-heterodyne type arranged to receive amplitude modulated carrier waves. The cathode of the discharge device 10 is grounded and the anode is connected through a tuned primary winding 11 of a transformer 12 to a suitable source of unidirectional current supply indicated at B. Such a supply source may be a battery having its negative terminal grounded. A tuned secondary winding 13 of the transformer 12 is connected to a series supply signal modulated oscillations to a series diode detector circuit comprising a low pass resistance-capacity filter 14, 15, 16, a diode load resistor 17 and the diode portion of an electron discharge device 18 of the double diode high-

mu triode type, known commercially as the 6SQ7.

It will of course be understood that the discharge device 18 need not be of the combined diode and triode type, but that the diode and triode sections may suitably be sealed in separate evacuated envelopes. The discharge device 18 comprises a cathode 19 and a first anode 20 constituting a diode section, and a second anode 21 and control grid 22 constituting with the cathode 19 a triode section. The diode section of the discharge device 18 is connected as a detector in the manner described above, and the triode section is connected as a signal amplifier, as will be more fully described hereinafter. The output of the amplifying section of the discharge device 18 is impressed upon a suitable load resistor 23, and through a blocking condenser 24 to the control electrode or grid of a second stage 20 of signal amplification comprising an electron discharge device 25. The control electrode of the discharge device 25 is connected to ground through a suitable grid leak resistor 25a, and the output current of the device is supplied to a suitable signal reproducing apparatus 26, such as a loud speaker, headphones, a cathode ray device, or the like.

Referring now to the series diode detector circuit comprising the diode elements 19 and 20 within the discharge device 18, it will be observed that I have shown connected in parallel circuit relation with the diode load resistor 17 a direct current blocking condenser 27 and a volume control resistor 28 in series circuit relation. The volume control resistor 28 is grounded at one end, as is the diode load resistor 17, and a portion of the volume control resistor adjacent the grounded end is shunted through a base compensation network comprising a resistor 29 and a condenser 30 connected in series circuit relation. The function of the base compensation circuit in the reception of audible signals, such as voice, music, and the like, is well understood by those skilled in the art. The base compensation emphasizes the response of the audio amplifier to low and intermediate audio frequencies as distinguished from high audio frequencies. The volume control resistor 28 serves as a potentiometer, across a selectable portion of which a signal potential of desired strength may be taken off by a sliding contact 31 and impressed through a blocking condenser 32 between the control grid 22 and cathode 19 of the signal amplifying triode section of the discharge device 18. Suitable grid bias is provided for the control grid

22 by a bias resistor 33 connected between the control grid 22 and the grounded cathode 19 of the discharge device 18.

A phonograph pick-up 34 is permanently connected, preferably, through a shielded cable 35, to an intermediate point on the volume control resistor 28. As shown at Fig. 1, this intermediate point may suitably be the point of connection of the base compensation circuit 29, 30, since that portion of the resistor 28 between this point and ground provides approximately proper loading for the phonograph signal.

In the operation of the arrangement shown in Fig. 1, it will be understood that, when the phonograph pick-up 34 is not in operation and the radio receiving apparatus is tuned to a station, signal frequency oscillations are supplied across the entire volume control resistor 28 by demodulation in the diode section of the discharge device 18. These signal oscillations are attenuated as desired and supplied to the signal amplifying section of the discharge device 18 through the volume control slider 31 and condenser 32, amplified in the devices 18 and 25 and reproduced in the usual manner. If now it is desired to change to phonograph reproduction, the phonograph is set in operation to impress signal frequency oscillations from the pick-up 34 across the base compensation section of the volume control resistor 28. This lower section of the volume control resistor now serves as a potentiometer, across a selectable portion of which the phonograph signal oscillations of the desired intensity may be chosen by the volume control slider 31 and applied to the signal amplifying devices. It will of course be understood that if, during such phonograph reproduction, the radio receiving apparatus is left tuned to a station, a certain amount of radio interference will be encountered despite the fact that the upper section of the volume control resistor 28 provides substantial attenuation of the radio signal. Such interference may be substantially eliminated very simply by the operator merely by detuning the radio receiver to some point between stations.

At Fig. 2 I have shown another embodiment of my invention in which radio interference with phonograph reproduction is entirely eliminated, despite the maintenance of a permanent connection between the phonograph pick-up and the volume control resistor. Except for the connection to the volume control resistor, the apparatus of Fig. 2 is entirely similar to that of Fig. 1 and like parts have been assigned the same reference numeral. It will be noted that at Fig. 2 the volume control resistor is grounded at an intermediate point, rather than at one end, and that the radio signal is impressed across that section of the resistor 28 between the grounded point and the upper terminal, while the phonograph signal is impressed across an entirely separate section of the resistor 28 between the grounded point and the opposite terminal of the resistor. To provide proper loading for the signal from the phonograph pick-up 34, a condenser 36 in series with a resistor 37 is shunted across the phonograph section of the resistor 28. The values of this condenser and resistor should be chosen to provide the most pleasing frequency characteristic for phonograph reception.

In the operation of the apparatus shown in Fig. 2, it will be evident that the adjacent sections of the volume control resistor 28 on opposite sides of the grounded intermediate point

serve as separate potentiometers for the demodulated signal voltage from the radio apparatus and for the signal voltage from the phonograph apparatus. Since the radio and phonograph signal voltages appear across entirely separate portions of the volume control resistor, they do not interfere with one another in any way. Thus both signals may be simultaneously impressed upon the resistor 28 and may be selectively chosen for application to the audio amplifying devices by positioning the volume control slider 31 either above or below the grounded point of the resistor 28.

While I have shown and described only certain preferred embodiments of my invention by way of illustration, modifications thereof will undoubtedly occur to those skilled in the art, and I therefore wish to have it understood that I intend in the appended claims to cover all such modifications as fall within the true spirit and scope of my invention.

What I claim as new and desire to secure by Letters Patent of the United States is:

1. A combination radio-phonograph receiving and reproducing apparatus comprising a source of signal modulated electric oscillations, a resistor, means for deriving from said source and impressing across at least a portion of said resistor oscillations at signal frequency in accordance with said signal modulation, a phonograph pick-up permanently connected to said resistor for impressing other signal oscillations across a portion of said resistor, and means variably responsive to the signal oscillations appearing across selectable portions of said resistor for reproducing said signals.

2. A combination radio-phonograph receiving and reproducing apparatus comprising a source of signal modulated electric oscillations, a resistor having one end permanently connected to a point of fixed potential, means for deriving from said source and impressing across said resistor oscillations at signal frequency in accordance with said signal modulation, a phonograph pick-up permanently connected across a portion of said resistor including said point of fixed potential to impress across said portion other signal oscillations, and means variably responsive to the signal oscillations appearing across selectable portions of said resistor for reproducing said signals.

3. A radio-phonograph receiving and reproducing apparatus comprising a source of signal modulated electric oscillations, a volume control resistor, means for deriving from said source and impressing across said resistor oscillations at signal frequency in accordance with said signal modulation, a phonograph pick-up permanently connected to an intermediate point on said resistor for impressing other signal oscillations across a portion of said resistor, said portion of said resistor providing maximum attenuation of said first signal oscillations, and means variably responsive to the signal oscillations across selectable portions of said resistor including said portion of maximum attenuation for reproducing said signals.

4. A combination radio-phonograph receiving and reproducing apparatus comprising a source of signal modulated electric oscillations, a volume control resistor having one end connected to a point of predetermined fixed potential, a base compensation network connected between said point of fixed potential and an intermediate point on said resistor, means for deriving from said

source and impressing across said resistor oscillations at signal frequency in accordance with said signal modulation, a phonograph pick-up permanently connected to said intermediate point of said resistor for impressing other signal oscillations between said intermediate point and said point of fixed potential, and means variably responsive to signal oscillations between said point of fixed potential and selectable points on said resistor for reproducing said signals.

5. A combination radio-phonograph receiving and reproducing apparatus comprising a source of signal modulated electric oscillations, a resistor, means for deriving from said source and impressing across a first portion of said resistor oscillations at signal frequency in accordance with said signal modulation, a phonograph pick-up permanently connected to impress other signal oscillations across a second portion of said resistor, and means variably responsive to signal oscillations appearing across said portions of said resistor selectively to reproduce said signals.

6. A combination radio-phonograph receiving and reproducing apparatus comprising a source of signal modulated electric oscillations, a volume control resistor having an intermediate point permanently connected to a point of predetermined fixed potential, means for deriving

from said source and impressing across a first portion of said resistor including said intermediate point oscillations at signal frequency in accordance with said signal modulation, a phonograph pick-up permanently connected to impress other signal oscillations across a second portion of said resistor including said intermediate point, and means variably responsive to signal oscillations between selectable points on said resistor and said intermediate point for reproducing said signals.

7. A combination radio-phonograph receiving and reproducing apparatus comprising a source of signal modulated electric oscillations, a volume control resistor having a point of predetermined fixed potential, means for deriving from said source and impressing across at least a portion of said resistor including said point of fixed potential oscillations at signal frequency in accordance with said signal modulation, a phonograph pick-up permanently connected to impress other signal oscillations across a portion of said resistor including said point of fixed potential, and means variably responsive to signal oscillations between said point of fixed potential and selectable points on said resistor for reproducing said signals.

CARROLL R. MINER.
